(57) **CLAIM**

The ornamental design for a wall buffer, as shown and described.

DESCRIPTION

FIG. 1 is a front top perspective view of a wall buffer in accordance with the new design;

FIG. 2 is a front bottom perspective view thereof;

FIG. 3 is a front elevation view thereof;

FIG. 4 is a rear elevation view thereof;

FIG. 5 is a top elevation view thereof;

FIG. 6 is a bottom elevation view thereof; and,

FIG. 7 is a right side elevation view thereof; the left side view being a mirror image.

The wall buffer is shown with a symbolic break along its length. The appearance of any portion of the article between the break lines forms no part of the claimed design.

The dashed lines shown are for illustrative purposes only and form no part of the claimed design.
